(57) **CLAIM**

I claim the ornamental design for a tomato knife, as shown and described.

DESCRIPTION

FIG. 1 is a top perspective view of a tomato knife, showing my new design.

FIG. 2 is a top view of the tomato knife.

FIG. 3 is a front view of the tomato knife.

FIG. 4 is a back view of the tomato knife.

FIG. 5 is a right side view of the tomato knife.

FIG. 6 is a left side view of the tomato knife; and,

FIG. 7 is a top perspective exploded view of the tomato knife, shown with a handle and blade separated from a sheath of the tomato knife. The blade extending from the handle is shown in phantom and forms no part of the claimed invention.
